SPENCER OTIS, OF CHICAGO, ILLINOIS.

METHOD OF AND SYSTEM FOR WASHING OUT BOILERS.

Application filed January 29, 1920. Serial No. 354,767.

To all whom it may concern:

Be it known that I, SPENCER OTIS, a citizen of the United States, residing at Chicago, in the county of Cook and State of Illinois, have invented certain new and useful Improvements in Methods of and Systems for Washing Out Boilers, of which the following is a specification.

This invention relates to a method of and a system of apparatus for washing out boilers, particularly steam boilers, and more especially locomotive boilers, and proceeds upon the underlying principle of stirring up the sediment in a boiler to bring it into a state of suspension in the contained water of the boiler, and then drawing it off with the water serving as a vehicle.

The primary object of the invention is to provide a method of procedure which may be carried on with economy of time and labor, with high efficiency in operation, and with comparatively simple and inexpensive apparatus.

Accordingly, one feature of the invention consists in blasting into a boiler, while under pressure or while closed against the escape of such pressure as may accumulate therein, and in agitating relation to the contained water, a gaseous medium, hereinafter referred to as "air", having the characteristics of resisting absorption in water, expanding under the heat of the boiler, and readily separating from the water when permitted, and thereby stirring up the sediment or precipitate in the boiler and bringing it into a state of suspension in the contained water, and then driving out the sediment or precipitate with the water serving as a vehicle; the pressure for discharging the water with the stirred up sediment being provided either by the normal boiler pressure or by the accumulation of the air, or by both.

Another feature consists in utilizing the air introduced into a boiler, under the conditions above recited, for the purpose of increasing the heat units recovered from the blown off water or blown off steam or vapor, or both; this being accomplished by separating the air from the water after it performs its stirring function and passing it to a condenser, the water from which flows to a filling tank. The separation may take place in the boiler, in which instance the air with its heat and moisture, gathered in

passing through the water, flows from the steam space of the boiler, either alone or in conjunction with steam, through the steam blowoff pipe to the condenser; or if the air passes out with the blown off water it goes to a separator where it rises as heated moist air, along with steam and vapor, and passes to the condenser. In either instance, the heated moist air supplies a material increment in the heat units salvaged.

Another feature consists in replenishing the water of the boiler as the water blowoff proceeds, thereby keeping up the water supply, preferably by injecting hot water, and, when desirable, initially raising the level of the water above the normal stage to cause submergence of the air delivery jets and insure proper stirring effect.

Still another feature consists in carrying on the procedure of washing the boiler under the condition of replenishing the water as the blowoff proceeds, with or without any or all of the other conditions above stated, without drawing the fire. The water introduced for keeping up supply may be at such temperature that it will permit the generation of steam to continue during the procedure.

A further feature consists in combining, in a system of apparatus for practicing the process under any or all of the preceding conditions, an air injector, steam and water blowoff lines, and a filling line, all adapted to be connected at will with the boiler of a locomotive; also a vapor and water separator receiving the discharge of the water blowoff line, a condenser receiving steam or vapor from the separator and from the steam blowoff line, and a filling tank receiving water from the condenser and supplying it to the filling line.

Still a further feature in the apparatus employed consists in a water stirring means of the air-blast type located in a boiler above the normal water line therein so that it remains unimpaired by scale, but at a stage permitting it to be readily submerged by raising the water above the normal level in the boiler in order to insure proper stirring action; also means for raising the water level at will, and means for supplying air under pressure to such stirring device.

In the accompanying drawings—

Figures 1 and 1^a together constitute a

schematic view showing one arrangement of the system capable of carrying out the method herein referred to.

Figure 2 is a horizontal section on the line 5 2^x—2^x of Figure 3, immediately above the crown-sheet of the boiler and looking upward; and

Figure 3 is a vertical section on the line 10 3^x—3^x of Figure 2.

1 represents a steam-receiving pipe in a roundhouse or other location where it is desired to blow off locomotive boilers; and 2 represents flexible connectors by which such pipe may be connected with the blow-off 15 3 of a locomotive which may be controlled by a valve 4. 5 represents a filling line supplying water for refilling the boiler, and 5^a is the circulating line for keeping up circulation and proper temperature of water 20 in pipe 5 when water is not being drawn therefrom for use. 6 represents a filling station on the pipe-line 5, adapted for attachment of filling hose 6^a. 7 represents a pipe which is supplied, under pressure, with air 25 or other blast medium of a character that will not absorb in water. Said pipe 7 is provided with connecting stations 8, and constructed for attachment of hose or other flexible connectors 9. The connectors 9 are 30 adapted to be attached to nipples 10 tapped into the shell of the boiler at a number of different places advantageous for attacking the sediment, sludge, or precipitate upon the inner surfaces of the boiler. There may be 35 any desired number of these nipples 10. 11 represents the water blowoff pipe, and 11^a its hose connection, which might connect directly to the sewer, but which is preferably connected with the steam blowoff pipe 1 so 40 that the heat units in the impure water may be extracted. For this purpose, pipe 1 has interposed in it a separator 12 where steam and vapor may rise from the water, and from separator 12 the steam pipe 1 leads to a condenser 13 where said steam and vapor are 45 condensed.

When a connector 9 is applied to a nipple 10 and the compressed air or other gaseous medium under pressure is released to the connector, a violent blast is discharged into the boiler in stirring relation to the water contained therein, and preferably also in impinging relation to the surface from which the precipitated matter is to be dislodged. 50 By this means the precipitated foreign matter is displaced from the surface and so stirred up in the water that it will remain suspended in the water and flow out, with the water serving as a vehicle for its removal. 55 The procedure of blasting in the dislodging and stirring medium preferably takes place after the pressure of the boiler has been considerably or wholly reduced. If the compressed air is supplied at a pressure of sixty 60 or seventy pounds to the square inch, it will

be well to reduce the pressure of the boiler to at least thirty pounds. It may be reduced to mere atmosphere. While there is an advantage in leaving some of the pressure for use in driving out the refuse and water through the pipe 11, gravity may suffice for this, or the influence of gravity may be augmented by pressure induced by the accumulating air, to which end, the boiler is closed during the air blasting. 70 75

It may be desirable to continue the blasting and agitation for a part of the time that the water and sediment are being drawn off through the water conduit 11. It is very desirable to replenish water in the boiler not only for such period of time as will be necessary to thoroughly remove the dislodged precipitate, or until clear water escapes from the discharge hose 11, but also so long as water is being discharged, since this permits the fire to be retained under the boiler during the operation. Accordingly, the replenishing water pipe 6, equipped with connector 6^a which may correspond to the usual filling pipe, is connected up during 80 the operation. By combining water pipe 6 with the blast pipe 9 and drain pipe 11 new results are obtained, in that ample water for holding the precipitate in suspension is insured at the outset, agitation and stirring 85 may be continued until the water runs clear, and fire may be retained in the boiler while washing out. 90 95

The air delivered through the uppermost nipple 10 is preferably distributed over the 100 crown-sheet 14 (Figure 3) by some such arrangement as the pipe 15 (Figures 2 and 3) having the jet nozzles 16. These air nozzles are above the normal water level of the boiler so as to preserve them from impairment by scale, but in such position that they may be readily submerged by introducing enough water to raise the level to an abnormal stage. This will be done before starting the air blast, and will be continued as 110 an incident of replenishing water during the blowoff. That is to say, before releasing the air through the distributing nozzle 16, the water level, which would normally stand but slightly above the crown-sheet, will be 115 considerably raised so as to submerge pipe 15, and also to insure ample body of water to suspend and convey the stirred up precipitate and render safe the retention of the fire by insuring maintenance of sufficient 120 water throughout the procedure of stirring up and blowing off. 125

By the use of a non-absorbing medium such as air for the blasting medium, the eroding, dislodging, and stirring effects are 130 greater; the large volume of the air resulting from its release in the boiler and absorption of heat from the water is added to that of the steam as a conveyor of heat units through the separator to the condenser; 135

an increased quantity of steam or vapor is borne upward by the escaping air into the steam space of the boiler and out through the blowoff; and circulation through the 5 blow-off pipe to the condenser can be maintained after the steam pressure is dissipated.

That portion of the apparatus shown in Figure 1^a may correspond in detail to boiler filling systems made known prior to the present invention or disclosed in previously filed patent applications, differing, however, in the omission of the wash water collecting and return elements. Here, blowoff steam and accumulated agitating air from the locomotive dome 3 pass through pipe 1 directly through the separator 12 to the condenser 13 where they meet water from spray nozzle 18 released thermostatically by valve 19 under control of the thermostat 19^a which is 10 responsive to the presence of steam in the condenser, resultant warm water being delivered through pipe 20 to filling tank 21, whence it is returned by pump 22 through filling line 5. Similarly, water blown off 15 through connections 11 and 1 reaches separator 12, and the steam, hot air, and vapor therefrom pass over to condenser 13, greatly increasing the quantity of heat units saved.

In order to compensate for loss of heat 20 in the tank 21 and keep up the temperature of water issuing therefrom, a heater 23 connected by pipe 24 with the pipe 20 that leads to tank 21, is provided with a steam pipe 25 delivering steam thereinto, preferably exhaust steam from the engine 22, and with a spray nozzle 26 delivering water to condense said steam and provide hot water for the tank. This nozzle 26 is connected with the filling line 5 through the medium of a pipe 27 which is controlled by by-pass valve 28 that is in turn controlled by thermostat 28^a in the pipe 29 which connects the feed pump 22 with the tank. Pipe 27 is relatively smaller than the pipe of the filling line 5, 25 so that it does not draw from the latter sufficient water to interfere with the supply at the drops; moreover, the pump being controlled by pressure on the line, as is usual in systems of this kind, and as hereinafter described, a drop in pressure on the discharge side of the pump, due to the opening of by-pass 28, will at once be compensated for by increased output of the pump. Accordingly, whenever the temperature of 30 water passing thermostat 28^a falls below a predetermined degree, valve 28 is opened, water flows through the heater 23 and back to the tank 21, and the temperature of water in the tank is raised. Heater 23 is preferably the auxiliary condenser, normally receiving exhaust steam from the engine and condensing water from the return pipe 5^a of the washout line, as described and claimed in the copending application of Frank S. Wichman, Serial No. 323,445. By having an auto-

matically controlled by-pass for the water, the heating effect is much more prompt and direct than when the water makes the entire circuit and returns to the heater through the pipe 5^a. 70

Supply of water in tank 21 will be maintained by having a float 30 or other form of water level control acting upon a valve 31 which controls a steam pipe 32 communicating with condenser 13 so that when the level of water in the tank descends below a predetermined limit, steam will be released to the condenser and will act upon the thermostat 19^a and open the water valve 19 to maintain a supply of hot water through 75 pipe 20 to the tank 21 until the rise of the water level in the tank closes valve 31, as described in my copending application Serial No. 308,616. 80

The pump 22 will have its steam pipe 33 controlled by valve 34 which is in turn subject to control by a known form of pressure element 35 in the filling line 5, so that the action of the pump is always commensurate with the demand on the filling line, as is 85 usual with systems of this kind. 90

I claim:

1. The improvement in the art of washing out steam boilers while under pressure, which consists in delivering into the boiler, 95 under a pressure sufficient to overcome the pressure of the boiler and causing to rise through the water of the boiler a gas that is non-absorbing in the water, thereby bringing the sediment to a state of suspension in 100 the water, collecting the added gas under pressure in the steam space of the boiler and evacuating the resultant water and sediment by pressure within the boiler.

2. The improvement in the art of washing out steam boilers while under pressure, which consists in delivering into the lower portion of the boiler, under pressure sufficient to overcome the pressure of the boiler and causing to rise through the water of the 105 boiler simultaneously at a plurality of widely distributed points therein and while the water is hot a gas that is non-absorbing in the water, thereby bringing the sediment to a state of suspension in the water, 110 collecting the added gas at increased temperature and tension in the steam space of the boiler and evacuating the water and sediment by resultant pressure within the 115 boiler. 120

3. The improvement in the art of washing steam boilers, which consists in injecting a non-absorbing gas to bring the sediment of the boiler to a state of suspension in the water therein, and evacuating the impure water by the pressure of the contained steam combined with that of the added gas. 125

4. The improvement in the art of washing steam boilers, which consists in delivering a non-condensing gas into agitating relation 130

to the water in the boiler, to stir up the sediment and to bring it into a state of suspension in the water, accumulating the added gas in the steam space of the boiler, removing the resultant impure water, and replenishing the water supply as the impure water is removed.

5. The improvement in the art of washing boilers, which consists in delivering a non-condensing gas into agitating relation to the water in the boiler to stir up the sediment and bring it into a state of suspension in the water, collecting the added gas in the steam space of the boiler, removing the resultant impure water, and replenishing the water supply by adding hot water as the impure water is removed.

6. The improvement in the art of washing boilers, which consists in delivering a non-condensing gas into agitating relation to the water in the boiler to stir up the sediment, collecting the added gas in the steam space of the boiler, removing the resultant impure water, and replenishing the water supply as the impure water is removed; the generation of steam in the boiler being maintained during the procedure.

7. The improvement in the art of washing steam boilers, which consists in delivering a non-condensing gas into agitating relation to the water in the boiler while under pressure to stir up the sediment therein and bring it into a state of suspension in the water, collecting the added gas in the steam space of the boiler and driving out the impure water by the resultant internal pressure of the boiler; the fire being maintained in the fire box and pressure being kept up in the boiler during the procedure.

8. The improvement in the art of washing boilers which consists in injecting air under pressure into agitating relation to the contained water while the water is hot, bringing the sediment into a state of suspension in the water, adding the resultant heated air to the steam in the steam space of the boiler, while maintaining the pressure of the boiler, and evacuating the impure water by the action of such pressure.

9. The improvement in the art of washing boilers, which consists in injecting air into the boiler in agitating relation to the contained water while the water is hot and under steam pressure, thereby heating the injected air and increasing its volume and bringing the sediment of the boiler into a state of suspension in the water, collecting the expanded hot air in the steam space of the boiler and evacuating the impure water by the action of the pressure resulting from the steam and injected air.

10. The improvement in the art of washing out boilers, which consists in raising the water level of the boiler above its normal level, stirring up the sediment of the

boiler to bring it into a state of suspension in the increased volume of water, and evacuating the impure water from the boiler; the water supply being replenished as the impure water is removed.

70

11. The improvement in the art of washing out boilers, which consists in raising the water level of the boiler above its normal level, stirring up the sediment of the boiler to bring it into a state of suspension in the increased volume of water, and evacuating the impure water from the boiler, the agitation being maintained and the water supply being replenished as the impure water is withdrawn.

75

12. The improvement in the art of cleansing boilers of precipitated foreign matter while under pressure, which consists in partially reducing the steam pressure of the boiler, then blasting into the boiler, and in agitating relation to the water contained therein, a gaseous medium not absorbable in water, thereby stirring up the foreign matter and adding the volume of the blasting medium to that of the boiler pressure, and then drawing off such foreign matter with the water serving as a vehicle therefor.

80

13. The improvement in the art of washing and refilling steam boilers, which consists in blasting into and in agitating relation to the body of water contained in the boiler, a gaseous medium non-absorbent in the water, thereby stirring up foreign matter in the boiler, and bringing it to a state of suspension, blowing off such foreign matter with the water serving as a vehicle therefor, together with steam and said gaseous medium, withdrawing steam or aqueous vapor and said gaseous medium from the blown-off products, and subjecting the same to a condenser, and delivering the resultant water of condensation to a refilling tank.

85

14. The improvement in the art of washing and refilling steam boilers, which consists in blowing off, condensing and delivering to a refilling tank a portion of the contained steam sufficient to bring the boiler to reduced pressure, blasting into and in agitating relation to the body of water contained in the boiler, a body of air that rises through the water, thereby stirring up the foreign matter and bringing it to a state of suspension in the water, and adding a volume of air to the steam space above the water, blowing off the foreign matter with the water serving as a vehicle therefor, together with the steam or aqueous vapor and moist air, separating said steam or vapor and air and delivering the same to a condenser, and delivering the resultant water of condensation to a filling tank.

90

15. The improvement in the art of washing and refilling steam boilers, which consists in blowing off, condensing and delivering to a refilling tank a portion of the con-

100

105

110

115

120

125

130

tained steam sufficient to bring the boiler to reduced pressure, blasting into and in agitating relation to the body of water contained in the boiler, a body of air that rises through 5 the water, thereby stirring up the foreign matter and bringing it to a state of suspension in the water, and adding a volume of air to the steam space above the water, blowing off the foreign matter with the water 10 serving as a vehicle therefor, together with the steam or aqueous vapor and moist air, separating said steam or vapor and air and delivering the same to a condenser, and delivering 15 to a filling tank; water being supplied from the filling tank to the boiler, and the water level in the boiler being kept up during the procedure.

16. An apparatus for washing out boilers, comprising a steam blowoff line, a line supplying air under pressure, a water blowoff line, a filling line, all of said lines being

adapted to connect with a steam boiler, a separator receiving water from the water blowoff line, means for condensing steam 25 or vapor from the steam blowoff line and the separator, and a filling tank receiving the water of condensation and supplying the filling line.

17. In combination with a steam boiler, a 30 blow-off line adapted to convey steam and air from said boiler, a compressed air line, delivery nozzles in said locomotive supplied by said compressed air line, a filling line, a separator receiving products from said blow-off line, a condenser receiving vapor and air from said separator, and a refilling tank receiving water of condensation from said condenser and supplying the same to said filling line. 35
